UNITED STATES PATENT OFFICE.

SAUL MITTLEBURG, OF ALTOONA, PENNSYLVANIA.

DISPLAY DEVICE.

1,317,307.

Specification of Letters Patent. Patented Sept. 30, 1919.

Application filed June 13, 1917. Serial No. 174,496.

To all whom it may concern:

Be it known that I, SAUL MITTLEBURG, a citizen of the United States, and a resident of Altoona, in the county of Blair and State 5 of Pennsylvania, have invented a new and Improved Display Device, of which the following is a full, clear, and exact description.

My invention has for its object to provide a display device having woven panels in the 10 openings in which brackets may be mounted for displaying articles.

Another object of the invention is to provide brackets for use in connection with the woven panels.

15 Additional objects of the invention will appear in the following specification, in which the preferred form of the invention is disclosed.

In the drawings similar reference characters denote similar parts in all the views, in which—

Figure 1 is a perspective view illustrating the display device;

Fig. 2 is a perspective view illustrating 25 one of the panels;

Fig. 3 is a perspective view illustrating the frame for receiving the panel illustrated in Fig. 2;

Fig. 4 is a sectional plan view of Fig. 1;

30 Fig. 5 is a perspective view illustrating one of the brackets which may be mounted on one of the panels for displaying articles;

Fig. 6 is a plan view of the blank used for constructing the bracket illustrated in Fig. 5;

35 Fig. 7 is a perspective view showing another bracket which may be mounted on the woven panel for supporting articles;

Fig. 8 is a plan view of the blank used in manufacturing the bracket illustrated in

40 Fig. 7; and

Fig. 9 is a perspective view illustrating a modified form of the invention.

By referring to the drawings, it will be seen that a rear frame 5 is provided, to the 45 sides of which side frames 6 are articulated, there being in addition two front frames 7 which are articulated to the sides of the side frames. While the two front frames 7 are illustrated in Fig. 7 of the drawings, only

50 one of these front frames is illustrated in Fig. 5, the second front frame being omitted to better illustrate the manner in which a piece of paper or other covering may be used to cover the split wood weave 9 with which

55 the panel 10 is provided, this panel 10 being normally disposed against the side frame 6

and being held in this position by L-hooks 11 which are adapted to be disposed through slots 12 in the panel 10 and be turned to hold the panel 10 in position. In a similar manner a panel 13 is held in position against the rear frame 5, and a panel 14 is held against the front frame 7.

The woven panels are provided as a means for supporting brackets, the brackets having 65 tongues which may be disposed between the split wood members of the weave, and being provided with legs or depending portions for engaging the outer surfaces of the weave. In this manner the brackets may be adjusted 70 relatively to the display device as may be desired, and be held in position after adjustment. When a paper or other covering 8 is employed, cuts 30 are made in the paper or other covering, which register with that portion of the weave in which the tongue of the bracket is to be disposed.

In Fig. 5 of the drawings there is shown in perspective one of the brackets employed, this bracket being constructed of the blank 80 illustrated in Fig. 6, and having a body 15 with a rearwardly extending tongue 16 and lateral wings 17. The tongue 16 is bent downwardly at the point where it is connected with the body 15, and the wings 17 85 are bent downwardly at the dotted lines 18. The tongue 16 of this bracket may then be inserted and pressed downwardly in an opening in the weave, and the wings 17 will engage the outer surface of the weave to hold 90 the body 15 of the bracket horizontally.

When the bracket illustrated in Fig. 7 is employed, a blank such as is illustrated in Fig. 8 is made use of, this blank having a body 19 with a rearwardly extending tongue 95 20, the tongue having wings 21 one at each side, the wings being connected with the tongue adjacent the body, but being separated from the body so that when the tongue 20 is bent downwardly as illustrated 100 in Fig. 7, the wings 21 may be bent at right angles to the tongue. When this bracket is employed and the tongue 20 is pressed downwardly in an opening in the woven panel, the wings 21 will engage the outer 105 face of the woven panel to prevent the forward end of the body from moving downwardly out of position.

Still another form of bracket is employed, this form being illustrated at 22, and being 110 provided with a looped end 23 which is disposed in a recess 24 at the side of the frame,

the bracket 22 having a depending leg 25 for engaging the frame. This form of bracket has been made the subject matter of a separate application for Letters Patent filed June 13th, 1917, Serial No. 174,495.

In Fig. 9 of the drawings there is shown a rectangular device or table 26 having woven sides 27 in the openings in which the brackets which have been described may be secured for supporting articles which are to be displayed.

Having thus described my invention, I claim as new and desire to secure by Letters Patent:

- 15 1. In a display device, a frame, a woven panel having a member, disposed in the frame, a cover disposed over the panel and held between the panel and the frame, the cover having a cut registering with an edge 20 of the member of the woven panel, and a bracket having a tongue disposed through the cut in the cover engaging the said edge of the woven member, for the purpose specified.
- 25 2. In a display device, a panel having horizontal and vertical members woven together with a horizontal member disposed against the inner side of a vertical member, against the outer side of the next vertical member and against the inner side of a third vertical member, a bracket having a supporting tongue disposed over the edge of the horizontal member between the first and

third vertical members and down between the horizontal member and the second mentioned vertical member.

3. In a display device, a frame, a woven panel consisting of members, which cross each other, removably disposed in the frame, a detachable member disposed over the panel and held between the panel and the frame, and a bracket having a tongue disposed in an opening in the cover and between members of the woven panel disposed at the sides of the tongue and at the rear of other members of the panel.

4. In a display device, a frame, a woven panel having a member removably disposed in the frame, a detachable cover disposed over the panel and held between the panel and the frame, the cover having a cut registering with an edge of the member of the woven panel, and a bracket having a tongue disposed through the cut in the cover engaging the said edge of the woven member, for the purpose specified.

5. In a display device, a frame, horizontal and vertical members woven in the frame, and a bracket adjustable relatively to the frame and having a supporting tongue normally disposed between two of the vertical woven members and between a third vertical woven member and a horizontal member, the top of which is engaged by the supporting tongue.

SAUL MITTLEBURG.

Copies of this patent may be obtained for five cents each, by addressing the "Commissioner of Patents, Washington, D. C."
